UNITED STATES PATENT OFFICE.

WILLIAM JAMES EDWARD BEERE, OF LONDON, ENGLAND, ASSIGNOR TO RUSHMORES
LIMITED, OF LONDON, ENGLAND.

STARTING DEVICE FOR EXPLOSION AND OTHER ENGINES.

1,283,046.

Specification of Letters Patent. Patented Oct. 29, 1918.

Application filed September 21, 1915. Serial No. 51,790.

To all whom it may concern:

Be it known that I, WILLIAM JAMES EDWARD BEERE, a subject of the King of England, residing in London, England, have invented certain new and useful Improvements in Starting Devices for Explosion and other Engines, of which the following is a specification.

This invention relates to engine starting devices, and in particular when employed upon motor-cars, of the kind in which the armature of an electric motor, normally out of driving engagement with the engine, is shifted endwise by electromagnetic means to establish driving engagement between it and the engine for the purpose of starting the engine, and is automatically thrown out of driving engagement when the engine has begun to be revolved by its own power.

Some starters of the kind referred to have the disadvantage that the motor is caused to rotate before the driving connection between it and the engine is established, and moreover of permitting the supply of current to the motor to be maintained after the latter has been disconnected from the engine, with the result that the motor then attains an undesirable speed of rotation. It is an object of the present invention to provide against the motor being revolved before it is in driving engagement with the engine and against current being supplied to revolve the motor after such engagement has been interrupted.

According to the present invention, in an engine starter of the kind described, means are employed, operated by the endwise shift of the armature, to prevent operative current from passing through the armature unless it is in driving connection with the engine. The means employed to prevent current passing through the armature may either be such as to open-circuit the armature or to short-circuit it; in the former case, the means may take the form of a sleeve of insulating material upon the commutator and, in the latter case, they may conveniently take the form of a conductor supported upon the commutator, but insulated therefrom and adapted to provide a bridging path between the brushes while the armature is in the non-engaged position.

In order to prevent undesired maintenance of driving connection between the starter and engine, or the reestablishment thereof after it has been automatically interrupted,

it is preferred to employ a series "self-maintaining" relay in the motor circuit, and, preferably, a switch to operate the relay so constructed that it is automatically tripped if its handle is moved home. The relay is 60 preferably constructed to open its circuit at a predetermined minimum current so as to constitute a minimum cut-out.

Further novel details of construction of the switch for coöperation with the relay are 65 hereinafter described and pointed out in the claims.

In the accompanying drawings—

Figure 1 is a diagrammatic illustration of one construction of starter in which the circuit between the brushes is open when the armature is in the disengaged position, 70

Fig. 2 is a similar illustration of a modification in which the brushes are connected together while the armature is in the disengaged position, together with a relay and tripping push button, and 75

Fig. 3 is a diagrammatic end elevation of part of the switch employed in the arrangement shown in Fig. 1. 80

In the construction shown in Fig. 1 a series motor is provided whose armature A is slidable axially through its bearings against the thrust of a return spring B. On one end of the armature spindle is mounted a pinion 85 C adapted to engage with teeth upon the engine fly-wheel D, but normally held out of engagement therewith by the spring B when the latter is free to assert itself. At the commutator end of the motor is a circuit closer in 90

the form of two spring contacts E, E₁ which are normally open but which are closed by the coned outer periphery F₁ of a short sleeve F, mounted upon ball bearings on the armature shaft so as to rotate relatively to it but 95 so as to move axially with the shaft.

Energy is delivered from a battery G through a three-way switch H whose first contact H₁ is dead, whose second contact H₂ is connected through a resistance J to the 100 point of junction of the field windings A₁ of the motor with one brush, and whose third contact H₃ is connected to the free member of the pair E, E₁; the other member of this pair is connected to the other brush. The 105 movable arm of the switch is spring-controlled so as always to return to the contact H₁ when left to itself.

A dog H₄ is pivotally hung from the underside of the arm H, as seen in Fig. 3. 110

The dog is insulated from the arm and the latter is of sufficiently springy construction or mounting to allow the dog, by its engagement with the edge of the contact H_2 , to lift the arm clear of that contact on the return movement. The switch base is cut away at H_5 to allow the dog to hang free between the contacts H_1 and H_2 .

To start the engine the switch is first moved on to the contacts H_2 whereupon the field magnets alone of the motor are energized and these draw the armature endwise against the thrust of the spring B to cause the teeth of the pinion C to enmesh with the teeth on D . The teeth of the pinion and of the fly-wheel are pointed on their opposed ends to promote enmeshment. If enmeshment has duly occurred the spring contacts E, E_1 are closed but the sleeve F is so placed on the armature shaft that until enmeshment has occurred these contacts remain open.

If enmeshment has occurred and the switch arm is then moved on to the contact H_3 , the armature will receive current through E, E_1 and will start the engine. When the engine fires and drives the motor, the back electro-motive force generated in the armature cuts down the current flowing through the motor to a value at which the field magnet can no longer overcome the spring B . This, therefore begins to return the armature toward the position shown in Fig. 1, but before disengagement from the fly-wheel has occurred, the motor circuit is broken at E, E_1 . This leaves the spring unresisted by any magnetic pull so that it completes the disengagement of the armature pinion from the fly-wheel smartly and with certainty. The operator then releases the switch arm H and this flies back on to the contact H_1 passing over the contact H_2 without touching it, owing to the action of the trip-dog H_4 .

Should the pinion and fly-wheel fail to engage when the switch arm is put on to contact H_2 , and the arm be then moved on to the contact H_3 , the circuit is broken and the armature slides back into the position shown in Fig. 1 without any ill effect; the operation is then repeated.

In the arrangement shown in Fig. 2 a sleeve of metal K is mounted upon the commutator, but so as to be insulated from it, and the sleeve is so dimensioned that when the armature is in the disengaged position a bridging circuit is provided by the sleeve from brush to brush. At L is a relay upon which are two windings namely L_1 , herein-after referred to as the operating winding, and L_2 hereinafter referred to as the series winding. The former is energized from the battery G through a push-button M , the details of whose construction are shown in diagram in Fig. 2. The series winding L_2 is

energized only when the relay contact is closed, under which condition current flows from the battery through the series winding and the relay contact in series; this contact is shown at L_3 . The relay is therefore of the "self-maintaining" type, that is to say, when it has been energized by means of the operating coil L_1 it maintains its own contact closed by the current which flows through that contact. A pull-off spring L_4 serves to open the contact when the current in the winding L_2 falls to a predetermined lower value; in this way the relay operates as an automatic minimum cut-out.

The push-button is constructed with a sliding contact piece M_1 and a fixed contact piece M_2 . The former is normally in conducting contact with two detents M_3 , each of which is carried upon a springy limb O of the push-piece R . Each of these limbs carries at its lower extremity a tapered projection O_1 adapted to enter a conical recess M_4 in the center of the lower contact piece M_2 . Springs P tend to hold the contact piece M_1 in the upper position in which it is seen in Fig. 2 and a flexible connector Q is provided, connected in any convenient manner to a leading-in wire Q_1 . Above the detents M_3 the limbs O are sheathed with insulating material to prevent contact between them and the sliding piece M_1 at this part of their length. A lead Q_2 is connected to the contact M_2 .

In operation, when the push-piece R is pressed down the piece M_1 is carried down with the limbs O against the tension of the springs P , and when contact occurs between the pieces O_1 and the piece M_2 current flows from the leading-in wire Q_1 through the flexible connector Q , the piece M , the limbs O and the contacts O_1, M_2 to the lead wire Q_2 . As, however, the movement is continued, by the piece R being pushed home, the limbs O approach one another owing to the co-operation of the recess M_4 with the projections O_1 , and thus disengage the detents M_3 from the piece M_1 . The latter thereupon snaps back into its normal position under the action of the springs P and so breaks the circuit through the button, which may be said now to be tripped.

The effect of the circuit through the push-button being closed is to energize the operating coil L_1 of the relay; this closes its contact L_3 and the battery G thereupon sends current through the winding L_2 , the contact L_3 , the sleeve K and the field windings A_1 of the motor. When, therefore, the push-button is tripped by being pushed home, the relay maintains its own contact closed, although the operating circuit is now dead. When the armature is pulled into engagement with the fly-wheel it brings the commutator beneath the brushes and receives operative current to rotate it. This action is

gradual though rapid, since for a portion of the endwise movement of the armature the brushes bear both upon the commutator and upon the sleeve K. No contact is, however, 5 made with the commutator until after the pinion on the armature spindle has been brought into engagement with the teeth on the fly-wheel.

When the engine fires, the current is reduced to such a value that the relay acts as a 10 minimum cut-out and releases its armature; the motor armature is then returned into the disengaged position by the spring automatically, whether or no the push button is 15 held on negligently or has been released, as it should have been, by the operator. In effect, the construction of the push-button and relay transfers from the operator to the relay the duty of keeping current on to the 20 motor and the relay discharges its function automatically, so that current is not kept on longer than desirable irrespective of negligence on the part of the operator. It will be understood that with an ordinary push-but- 25 ton or switch, if the operator held it closed after the engine had fired, the armature would be thrown back into the engaging position after having become disengaged, which is highly undesirable, and would 30 probably mean destruction of the teeth on the pinion or fly-wheel, or both.

The above described constructions are given by way of example only, and other 35 constructions which prevent operative current traversing the armature to rotate it when it is not in driving engagement with the engine, fall within the scope of this invention. For example, the sleeve K may be a sleeve of insulating material. Furthermore, 40 other constructions of push-button or switch may readily be devised to be automatically tripped when moved home into the full-on position and such other constructions of push-button or switch when to be used for the 45 purpose hereinbefore described, fall within the scope of this invention.

What I claim as my invention and desire to secure by Letters Patent is:—

1. In an engine-starter, the combination 50 of a motor whose armature is normally out of driving engagement with the engine but is electro-magnetically shifted endwise to establish the said driving engagement, a body carried upon the commutator and so 55 situated thereon as to lie engaged between the brushes of the motor while the armature is in the non-engaged position and prevent operative current traversing the armature windings from brush to brush but of 60 such dimension in the direction of said endwise movement as to be brought out of contact with the brushes when the armature is in the engaged position, and means controlled by the electro-motive force generated 65 in the motor when the engine is accelerated

by its own power whereby the supply of current to the motor is automatically interrupted.

2. In an engine starter the combination 70 of, a motor whose armature is normally out of driving engagement with the engine but is electro-magnetically shifted endwise to establish the said driving engagement, means adapted to short circuit the brushes of the motor while the armature is in the 75 non-engaged position but to open the said short-circuit when the armature is in the engaged position, and means controlled by the electro-motive force generated in the motor when the engine is accelerated by its 80 own power whereby the supply of current to the motor is automatically interrupted.

3. In an engine starter the combination 85 of, a motor whose armature is normally out of driving engagement with the engine but is electro-magnetically shifted endwise to establish the said driving engagement, means operated by the endwise shift of the armature to prevent operative current from passing through the armature to rotate it 90 unless it is in driving connection with the engine, including a conductor supported upon the commutator but insulated therefrom and supported in such a position that it short-circuits the motor brushes while 95 the armature is in the non-engaged position but breaks its connection with the brushes when the armature is in the engaged position, means controlled by the electromotive force generated in the motor when the engine is accelerated by its own power, whereby the supply of current to the motor is automatically interrupted.

4. In an engine starter the combination 100 of, an electric motor which normally is out of driving engagement with the engine, electro-magnetic means to establish driving engagement between the motor and the engine, means controlled by the aforesaid 105 means to prevent current effective to rotate the armature being supplied to the armature unless the said driving engagement is operative, and a relay of the series "self-maintaining" type in the supply circuit to the 110 motor the said relay having its operating 115 circuit controlled by a switch which is automatically tripped when its handle is moved into the full "on" position.

5. In an engine starter the combination 120 of, an electric motor which normally is out of driving engagement with the engine, electro-magnetic means to establish driving engagement between the motor and the engine, means controlled by the aforesaid 125 means to prevent current effective to rotate the armature being supplied to the armature unless the said driving engagement is operative, and a relay of the series "self-maintaining" type in the supply circuit to the motor, the said relay having its operating 130

- circuit controlled by a switch having a circuit closing member and handle therefor so constructed that when the handle is moved home in the circuit closing position the said 5 circuit closing member is mechanically tripped from its engagement with the handle and moves into the open circuit position.
6. In an engine starter the combination of, an electric motor which normally is out 10 of driving engagement with the engine, electro-magnetic means to establish driving engagement between the motor and the engine, means controlled by the aforesaid means to prevent current effective to rotate 15 the armature being supplied to the armature unless the said driving engagement is operative, and a relay of the series "self-main-

taining" type in the supply circuit to the motor the said relay having its operating circuit controlled by a switch having a circuit closing member and handle therefor and a detent to connect the said circuit closing member with said handle which detent while the circuit closing member is in the circuit closing position is automatically 20 displaced to disengage the said member from the handle.

In testimony whereof I have signed my name to this specification in the presence of two subscribing witnesses.

WILLIAM JAMES EDWARD BEERE.
